(57) **CLAIM**

The ornamental design for a returnable aluminum alloy container and lid for perishable foods, as shown and described.

DESCRIPTION

FIG. 1 is a front elevational view of the returnable aluminum alloy container for perishable foods without the lid, the rear elevational view being identical to the front elevational view;

FIG. 2 is a top plan view of the returnable aluminum alloy container for perishable foods without the lid;

FIG. 3 is a right side elevational view of the returnable aluminum alloy container for perishable foods without the lid, the left side elevational view being identical thereto;

FIG. 4 is a lower perspective view returnable aluminum alloy container for perishable foods without the lid;

FIG. 5 is a front elevational view of the lid for the returnable aluminum alloy container without the returnable aluminum alloy container shown, the rear elevational view being identical to the front elevational view;

FIG. 6 is a top plan view of the lid for the returnable aluminum alloy container without the returnable aluminum alloy container shown; and,

FIG. 7 is a top perspective view of the lid for the returnable aluminum alloy container without the returnable aluminum alloy container shown.
